UNITED STATES PATENT OFFICE.

ROBERT ZAHN, OF PLAUE, GERMANY.

EMBROIDERY-MACHINE.

1,016,193.

Specification of Letters Patent. Patented Jan. 30, 1912.

Application filed December 17, 1909. Serial No. 533,508.

To all whom it may concern:

Be it known that I, ROBERT ZAHN, of Plauen, Saxony, in the Empire of Germany, have invented certain new and useful Im-
5 provements in Embroidery-Machines, of which the following is a specification.

My invention relates to an improved embroidery machine, in which the working movements of the mechanism are controlled
10 by a jacquard device.

In the accompanying drawing, Figure 1 shows those parts of the machine which are important for the understanding of this invention in side elevation, viewed from the
15 left, and Fig. 2 is a perspective view of a detail of Fig. 1.

At the front side of the embroidery surface α are, as is well known, series of needles 1 secured to rails 2, of which two for two
20 series of needles are shown, superposed in the present example, and which, together with the rods 3 form a rigid whole. The rods 3 are longitudinally movable in bearings 4, and are capable of being horizontally
25 reciprocated therein by means of mechanism not shown in the drawing, for the purpose of forcing the needles 1 with their threads through the embroidery surface α , to produce the embroidery design. The thread is
30 drawn off from the supply spool 8 and carried around the guide roller 7, to and over the two guides 6 and 5 and from here to the needle 1. At the moment in which the thread is to be drawn taut at the
35 needle 1, the roller 7 must be held stationary. To this end the roller 7 is provided with a ratchet wheel 9, with the teeth of which a pawl 10 is caused to engage, in order to stop the roller at the instant re-
40 quired. Each pawl 10 is arranged on a lever 11, and all these levers are connected or pivoted to a common connecting rod 12. Secured to the main shaft 13 of the machine is a cam 14, the circumference of which engages with
45 a roller 15, which is rotatably journaled at the end of the rod 12. Each revolution of the main shaft 13 causes the cam to raise the connecting rod 12, thereby releasing the roller 7 at the instant required for the take
50 up of thread by the needle 1.

Some embroidery patterns are sometimes enriched by a thick cord secured thereto in the form of a straight horizontal relief line. To this end arms 16 are secured at both ends
55 of the embroidery to a common shaft 17 (Fig. 2) allotted to each needle series. Ar-

ranged at the end of each arm is a hook 18. The two shafts 17 of the upper and lower needle series are movably connected by a connecting bar 19 in such manner that on 60 moving the bar both hooks 18 are simultaneously so moved toward the embroidery surface α as to precisely coincide with the line of points at which the needles 1 enter the embroidery. Thus, if a cord is carried 65 by the hooks 18 and the arms 16 are swung forward by the connecting bar into the position 16', shown in dotted lines, while the machine is running, the cord will be sewn or fixed by all the needles 1 of each series 70 to the embroidery surface α , which is the object of the cord inserting device 16, 17, 18, 19, just described. All working movements of the whole embroidery machine are controlled by a jacquard device and the 75 main shaft 13 effects the driving of all parts.

In the drawing the jacquard device is indicated by the square box 20, 21, 22, 23 and only those parts are shown which are essential for the understanding of the invention. 80

Secured on the shaft 24 of the jacquard device is a toothed wheel 25 having twice as many teeth as a toothed wheel 26 which is mounted on the main shaft 13 and with which it engages. Thus, while the shaft 24 85 makes one revolution, the main shaft 13 makes two revolutions. Secured to the shaft 24 is a cam having a cam groove 27, 28, 29, 30, within which is guided a roller 31 on the arm of a bell crank lever which is pivoted at 90 32. The portion between the points 27, 28 and the portion between the points 29, 30 of the cam groove are concentric with the shaft 24. Thus, as long as the roller 31 travels along these circular parts of the groove, the 95 bell crank lever 31, 32, 33 remains stationary and only when the roller is guided in the descending portion 29—28 and in the ascending portion 27—30, is the bell crank lever operated. Movably attached to the free 100 end 34 of the cord carrying lever 17, 16, is a coupling rod 35, the other end of which carries a head 36. The upper and the lower faces of this head 36 are each provided with a recess of which the lower one is adapted 105 to engage with the free end 33 of the cam operated lever, while the upper recess is capable of co-operating with one or the other of two stationary abutments 37, 38. The coupling rod 35 is loosely supported within 110 a head portion 39 of a rod 40 which from time to time is reciprocated in the directions

of the double arrow 41. The displacement of the rod 40 in these directions is due to the jacquard mechanism according to the nature of the pattern to be embroidered.

- 5 The operation of the described mechanism is as follows. Assuming the main shaft 13 to be rotating and all the mechanism partaking in the ordinary embroidery process to be in regular working. The needles 1 10 enter the cloth α and the connecting rod 12 releases the thread guide rollers 7 at the required intervals in which operation the lever 31 33 is constantly rocked without, however, producing any effect. Supposing 15 now the moment to have arrived in which a cord is to be attached to the embroidery. At this instant the jacquard causes the rod 40 to move so that the head 36 of the coupling rod 35 is removed from engagement 20 with the stationary abutment 37 and moved on to the lever end 33. Consequently when the roller 31 of the lever comes into engagement with the cam portion 29—28, the rod 35 will be moved to the right and then 25 the rod 40 is again moved to a small extent, in the opposite direction, whereby the head 36 comes into engagement with the abutment 38. By this operation the levers 16 are brought into the position 16'; and simultaneously 30 the connecting bar 19 is caused to strike with its abutment 42 against an abutment 43 on the connecting rod 12 whereby the two locking pawls 10 are lifted out of engagement with the teeth of the corresponding ratchet wheels 7. While all this 35 is taking place, two attendants have seized a long cord at both ends and inserted it in the hooks 18, and this cord is immediately sewn on by all the needles 1. As soon as this 40 sewing on is effected, for which only a few working movements of the needles 1 are required, the levers 16 are brought back to their initial position. To this end the rod 40 is so moved by the jacquard device that 45 the head 36 of the coupling rod 35 is moved from the stationary abutment 38 on to the lever end 33 and back again to the stationary abutment 37.
- In automatic jacquard devices as hitherto 50 used for embroidery machines, besides the rod 40, another automatic mover was necessary for the purpose of pushing the thread releasing rod upward as soon as the cord inserting mechanism 16, 17, 18, 19 became 55 operative. The object of the present invention is to bring about this necessary moving up of the rod 12 without the aid of a second jacquard driving member or mover by the movement of the rod 40 itself with the aid 60 of the two abutments 42, 43 whereby the automatic embroidery machine is greatly simplified. The manufacture of the machine is moreover accordingly cheapened and interruptions or difficulties in the work- 65 ing of the mechanism occur less frequently

than hitherto where the usual devices were used. Also the production of the perforations in the card slip, the so-called jacquard card, is simplified, because the special perforations for a second jacquard mover are 70 no longer necessary and consequently the number of errors in the embroidery patterns, often caused by negligence of the pattern maker, is thus considerably decreased.

I claim:

1. In an embroidering machine, sets of needles and means for operating the same, means for braking the needle thread supply, means for applying ornamental cords to the surface of the work, and means for operating 80 the latter means having devices attached thereto for acting upon the braking mechanism.

2. In an embroidering machine, sets of needles and means for operating the same, 85 means for braking the needle thread supply, means for applying ornamental cords to the surface of the work, means for operating the latter means having devices attached thereto for acting upon the braking mechanism, and an automatic jacquard for controlling 90 the means operating the cord applying means.

3. In an embroidering machine, sets of needles and means for operating the same, 95 means for braking the needle thread supply, means for applying ornamental cords to the surface of the work, a device for moving said latter means in and out of operative position, an automatic jacquard for controlling 100 said device and means coöperating with said cord applying mechanism for releasing the braking mechanism.

4. In an embroidering machine, a rocking mechanism for applying cords to the surface 105 of the work, a reciprocatory rod attached to said mechanism, an automatic jacquard device, and a connecting rod intermediate the jacquard and the reciprocating rod, and a cam operated lever for moving the said 110 reciprocating rod at predetermined times, said jacquard operating on said reciprocating rod to move the same from its normal connection with said cam operated lever.

5. In an embroidery machine, the combination with sets of needles and means for operating the same, of means for applying ornamental cords to the surface of the work, means for braking the needle thread supply, an automatic jacquard device, means controlled by the latter for operating both the cord applying means and the thread supply braking means and having devices attached thereto for acting upon the braking mechanism.

6. In an embroidery machine, the combination of means for applying ornamental cords to the surface of the work, sets of needles, means for operating the same, means for controlling the needle thread sup- 130

ply, an automatic jacquard device, means intermediate the latter and the cord applying means for controlling the latter, and co-operating means between the cord operating device and the thread controlling means for releasing the thread when the cord is applied to the work.

7. In an embroidery machine a cord applying device comprising a rocking arm, a cord support thereon, a rod for rocking said arm and a projection on said rod, a thread controlling mechanism comprising a toothed wheel and pawl, a rod to which said pawl is connected, and a lug on said rod adapted to engage with the projection, and means for moving the rod operating the rocking arm at predetermined times, substantially as set forth.

8. In an embroidery machine a cord applying device comprising a rocking arm, a cord support thereon, a rod for rocking said arm and a projection on said rod, a thread controlling mechanism comprising a toothed wheel and pawl, a rod to which said pawl is connected, and a lug on said rod adapted to

engage with the projection and an automatic jacquard controlled device for moving the rod operating the rocking arm at predetermined times substantially as set forth.

9. In an embroidery machine comprising 30 a cord applying mechanism, a thread controlling device and an automatic jacquard device, a driving shaft, a toothed wheel and a cam on said shaft, a rod connected to the thread controlling mechanism operated by 35 said cam, a second toothed wheel gearing with the said toothed wheel, a shaft carrying said second toothed wheel and forming the shaft of said jacquard device, a cam mounted on said shaft and a pivoted lever 40 operated by said cam and coöperating with the cord applying mechanism substantially as set forth.

In testimony whereof I have signed my name to this specification in the presence of 45 two subscribing witnesses.

ROBERT ZAHN.
